UNITED STATES PATENT OFFICE.

MILTON F. WILLIAMS, OF ST. LOUIS, MISSOURI.

DESIGN FOR A PULLEY.

SPECIFICATION forming part of Design No. 30,347, dated March 14, 1899.

Application filed January 30, 1899. Serial No. 703,911. Term of patent 14 years.

To all whom it may concern:

Be it known that I, MILTON F. WILLIAMS, a citizen of the United States, residing at the city of St. Louis, State of Missouri, have invented a certain new and original Design for a Pulley, of which the following is a full, clear, and exact description, reference being had to the accompanying drawings, forming part of this specification, in which—

10 Figure 1 is a perspective view illustrating a pulley whose face is ornamented and configured according to my new and original design. Fig. 2 is a longitudinal sectional view of a pulley whose face is ornamented and configured according to my new and original design.

15 This invention relates to a new and original design of a pulley, the essential characteristics of which are series of parallel circumferential grooves arranged close together on the face of the pulley, as shown.

In the drawings, A indicates a pulley whose face is ornamented with circumferential grooves parallel to each other and close together, said grooves, which are marked B in 25 the drawings, being substantially V-shaped in cross-section, or, rather, said grooves may be more correctly termed "truncated" in cross-section.

What I claim is—

20 The design for a pulley, substantially as herein shown and described.

In testimony whereof I hereunto affix my signature, in the presence of two witnesses, this 25th day of January, 1899.

MILTON F. WILLIAMS.

Witnesses:

F. R. CORNWALL,
W. M. H. SCOTT.
